FREDERICK SEYMOUR, OF EAST ORANGE, NEW JERSEY, ASSIGNOR TO AERO
PULVERIZER COMPANY, A CORPORATION OF DELAWARE.

PULVERIZER AND PROCESS OF FINE PULVERIZING.

1,363,361.

Specification of Letters Patent. Patented Dec. 28, 1920.

Application filed January 7, 1919. Serial No. 269,995.

To all whom it may concern:

Be it known that I, FREDERICK SEYMOUR, a citizen of the United States, residing at East Orange, in the county of Essex and State of New Jersey, have invented certain new and useful Improvements in Pulverizers and Processes of Fine Pulverizing, of which the following is a specification.

My invention relates to pulverizers adapted to reduce coal and coke to an impalpable powder by beating and friction and to mix the pulverized product with a desired portion of air for perfect or effective combustion, and to force the mixture direct to the furnace preferably, or else to the place of deposit or classification and to a process of fine pulverizing. Other friable materials may be pulverized.

The class of pulverizers to which the invention relates is that employing a series of concentric chambers from the feed end to the discharge end thereof, a horizontal shaft mounted centrally within these chambers and carrying a series of rotating spiders or disks to which paddles are secured so as to work in the concentric chambers. Separating the concentric chambers are peripheral diaphragms with axial openings for the passage of air and the material being pulverized.

At the discharge end of the pulverizer is a fan, on the same shaft, which induces a current of air through the pulverizer upon which the material in course of treatment will be borne successively from one chamber to the next and when pulverized will be discharged mixed with air through the fan.

Between the last pulverizing chamber and the fan preferably is an auxiliary air inlet for supplying such additional air as may be desired over and above the air needed for pulverizing, but the auxiliary air may be admitted elsewhere.

Pulverizers of this class are principally used to pulverize coal, to mix the powder with the air required for perfect combustion and to deliver the mixture to a furnace where the coal is burned in suspension like a gas. It has become a standard requirement in recent years that the coal should be re-

duced to such a fineness that 85% of it will pass a sieve or screen having 40,000 interstices to the square inch and more than 95% of it should pass a screen having 10,000 interstices to the square inch, and very slight excess of coarse particles over these standard commercial requirements are considered objectionable, and pulverizers heretofore in use, of the type above mentioned, have failed to produce a product of the required fineness, particularly after the pulverizing parts have become partially worn.

The standard requirements of the product above mentioned have become so thoroughly accepted that a pulverizer which cannot meet and maintain those requirements under ordinary conditions of wear, is not marketable.

The requirement has been adopted as a compromise between the power cost of finer pulverizing and the combustion advantages to be derived therefrom.

I have found after prolonged experiments that the required fineness may be secured by an adjustment of the relations between the diameters of the pulverizing chambers, the diameters of the axial openings in the diaphragms separating the chambers, and the diameters of the disks carrying the paddles, and that the herein described adjustment positively facilitates the process of air separation within the pulverizer, whereby the too coarse particles are thrown into the pulverizing zones, while the sufficiently fine particles are borne by the axial air current through to the discharge.

In the class of pulverizers in which the diameters of the pulverizing chambers increase from the feed end toward the discharge end, this adjustment may be made by maintaining the same or nearly the same diameter for the axial openings in the diaphragms throughout the pulverizing part of the machine, and increasing the diameters of the paddle carrying disks from the feed end of the machine toward the discharge end, commencing in the first chamber with a disk which is of less diameter than the axial opening of the diaphragm, through which that chamber discharges, and successively

increasing the diameters of the paddle carrying disks until the last one is as large or larger than the axial opening in the diaphragms on either side of it.

- 5 In pulverizers of the class where the pulverizing chambers are all of the same diameter, I make the relative adjustments by varying the diameters of the axial openings in the diaphragms on either side of the pulverizing chambers from the feed end of the machine toward the discharge end making the axial opening in the first diaphragm of a diameter larger than that of the revolving disk in the first chamber, and gradually decreasing the diameters of the axial openings in the other diaphragms until the diameters of the axial openings on either side of the last chamber become less than the diameter of the disk revolving in that chamber. In 10 this class of pulverizer the diameters of the paddle carrying disks are preferably all of substantially the same diameter.

I have described the preferable adjustment of parts but this may be varied without departing from the spirit of my invention, so long as the adjustment of disks in and diaphragms on either side of pulverizing chambers progresses in such way that the disk in the first chamber is smaller in 15 diameter than the axial opening in the diaphragm through which it discharges and the disk in the last chamber is in diameter as large as or larger than the axial openings on either side.

35 By the described adjustment, I relate the carrying power of the current of air passing axially through the machine to the size of the particles which are to be carried through the several chambers.

40 By the described adjustment, I further decrease the thickness of the tubular sheet of air as it passes axially through the pulverizing chambers from the feed end of the machine toward the discharge end, and I 45 increase the bends or waves in this axial current as it passes from the feed toward the discharge of the machine, and in the class of pulverizers above mentioned in which the diameters of the pulverizing 50 chambers increase from the feed end toward the discharge end and in which the diameters of the disks may correspondingly increase, it is obvious that the particles being pulverized when passing the disks are compelled to travel on curves of increasing 55 radii. Like successive results may be realized in the class of pulverizers in which the pulverizing chambers are of uniform diameter by successively increasing the diameters 60 of the disks and decreasing the length of the arms or lugs carrying the paddles. If it be desired that the paddles and arms or lugs carrying them shall be uniform throughout the pulverizing chambers, the radii of the 65 disks and consequently of the curves in

which the particles travel will nevertheless increase appreciably, inasmuch as the preferable construction in such case is one in which the paddles rotating in the first chamber are the farthest from the peripheral lining of the chamber, those in the last chamber are nearest to the lining and those in the intermediate chambers are at intermediate distances from the lining, thus permitting an appreciable increase in the diameters of the disks from the feed end toward the discharge.

Machines of this character revolve at high speed, the peripheral speed of the outer edge of the paddles, when the machine is in operation, being from 10,000 to 14,000 feet per minute, and the power of the axial current to carry particles between the disks and diaphragms from the feed end of the machine successively through the several chambers 85 toward the discharge end is affected by the centrifugal throw induced by this high speed of the revolving paddles, and the effect of the centrifugal throw relative to the carrying power of the axial current varies 90 in the successive chambers, being the greatest in the first chamber, where the particles are relatively large, and the least in the last pulverizing chamber where the particles are very fine. For this variation compensation 95 is made by the described adjustment.

Prior to my discoveries the paddles were usually carried by spiders of which the hubs were smaller than the axial openings through the diaphragms on either side, the 100 axial air current measuring on a radial line was relatively thick, offering substantial resistance so that particles of material passed in a spiral line from the first pulverizing chamber to the fan without other substantial deflection, being carried through on the axial current of air so near to the axis of the pulverizer that the operation of centrifugal motion upon the small but too coarse particles was often insufficient to 110 force them out of the axial current to the periphery, with the result that coarse particles in substantial quantities were carried through the machine without being reduced to the desired fineness.

An exception to the foregoing construction is a pulverizer which has not come into commercial use in which the axial opening in the first diaphragm is of smaller diameter than that of the paddle carrying disk in the 120 first chamber, the axial opening in the second diaphragm is of larger diameter than the paddle carrying disks in the second chamber, and the axial opening from the final pulverizing chamber into the fan is of 125 less diameter than that of the paddle carrying disks, the pulverizing chambers are of increasing width from the feed end toward the discharge end and the paddles carried by the revolving disks are of successively 130

decreasing widths and increasing lengths—a construction which tends to over-load and clog the first chamber and to defeat the purpose of fine pulverizing.

- 5 Some pulverizing is done in the first chamber and the remaining action is a treatment of fine particles. A moderate proportion of them are fine enough, and if all these could now leave the machine, leaving the 10 coarser particles behind, for further pulverizing, the action would be perfect. All prior pulverizers are partial failures here; but my improvements reach the coarser particles, mingled with some of the fine, it is 15 true, but reaches them, and my object is, by the described adjustment, in the successive chambers positively to direct the coarser particles and the current of air in which they are suspended farther and farther 20 from the axis of rotation as pulverizing progresses and by the same adjustment positively to decrease the radial dimension of a cross section of the axial current from the feed end to the discharge end of the 25 pulverizer and augment the waves or bends in said axial current, and concurrently to regulate and evenly distribute the work among the several chambers.

It is preferable that the described adjustment should be made progressively and about uniformly from one chamber to the next commencing at the feed end, but my invention is not limited to such relative dimensions but extends to any relative dimensions which commence with a paddle carrying disk of less diameter than that of the axial opening in the adjacent diaphragm and ends with a disk having a diameter equal to or larger than that of the axial 40 openings in the diaphragms on either side.

By the described adjustment the solid particles which are still too coarse to meet the aforesaid commercial requirements as they become finer and finer in their progress through the pulverizer exposing proportionately larger and larger surfaces to atmospheric resistance are nevertheless thrown out of the axial current to the periphery which is the pulverizing zone because concurrently with the reduction in size of the solid particles there successively occurs at coincident intervals an increase in centrifugal force, a decrease in the radial distance to be traveled by the particles to escape the axial current and an increase in the angle of deflection.

The disks are preferably of one piece cut from a steel plate and are fastened to the hub by shearing bolts with a cross section sufficient to keep the disk and the paddles revolving with the shaft unless an unusual obstruction, such as a railroad spike or bolt or other substantial piece of tramp iron or other metal should enter the pulverizer with

the coal as sometimes happens. The shearing of these bolts saves a bad wreck in the pulverizer. The paddles are carried on arms extending from the disk or they may be secured immediately to the disks by any suitable means.

By the described adjustment of the relative dimensions of the parts, I find that the load in the several chambers may be evenly distributed so that approximately an equivalent amount of work will be done in each 75 chamber, so that all chambers may be worked at maximum without clogging any of them, and I also find that a product may be produced of a fineness which will more than pass the commercial requirements 80 above referred to.

I find that the passage of the coarse particles across and out of the axial current and to the periphery is facilitated and made more certain by directing them into narrow 85 concentrated streams by means of radial or nearly radial grooves on the faces of the paddles, and finer pulverization results therefrom with no increase of power and with an appreciable increase in the output 90 of the pulverizer.

These paddles may be made of cast iron, but on account of the severe service required by them and the high speed at which they revolve and their consequent liability to 95 break if iron or other metal accidentally enters the pulverizer with coal, I have found it advantageous to make them of manganese steel and to obtain them from foundries operated by men skilled in the 100 composition, casting and heat treatment of manganese steel, and while the cost of cast manganese steel paddles, heat treated for ductility and to resist abrasion is high, the excess cost is more than offset by increased wearing qualities and freedom from 105 breakage.

I have found corrugations an inch wide and one-eighth of an inch deep across or partly across the face of the paddle, as 110 hereinbefore described, to work satisfactorily, but my invention is not limited to any dimensions, but extends to all sizes and shapes of ridges and depressions of the character described. It is desirable, but not 115 necessary, to case the paddles from two patterns, putting the ridges in one pattern where the depressions are in the other, and to place paddles from each pattern on alternate arms of each disk, otherwise the paddles have a tendency so to throw the material being pulverized, as to wear the linings of the pulverizers unevenly and in strips.

Other objects will appear from the here- 125 inafter description.

In order that my invention may be better understood, attention is directed to the ac-

companying drawings, forming part of this specification, in which—

Figure 1 is a vertical sectional view through a pulverizer of the type referred to which has pulverizing chambers of successively increasing diameter from the feed end 5 toward the discharge end.

Fig. 2 is a vertical section through a pulverizer of the type referred to in which the 10 pulverizing chambers are of uniform diameter.

Fig. 3 is a view looking longitudinally through the last pulverizing chamber, showing a form of the revolving parts and the 15 relative diameters of the disk thereof and of the axial openings on either side.

Fig. 4 is a view looking longitudinally through the first chamber showing a form of the revolving parts and of the relative 20 diameters of the first disk and of the first diaphragm.

Fig. 5 is a view in perspective of a corrugated paddle with lugs on the inner edge for attaching it to a disk without arms.

25 Fig. 6 is a view in perspective of a corrugated paddle with lugs on the back of it by which it may be attached to arms extending from the periphery of the disk.

In all the above views corresponding parts 30 are represented by the same numerals of reference.

1 is a base upon which is securely bolted the shell 2 of the pulverizing apparatus. Within the shell 2 of the pulverizing apparatus in the present instance are four concentric pulverizing chambers 3, 4, 5 and 6, an auxiliary air chamber 7, and a fan chamber 8. The pulverizing chambers are arranged concentrically. The chambers referred to are separated by the diaphragms 9, 10, 11, 12 and 13. Mounted centrally in the apparatus is a shaft 14, driven by any suitable means, such as a direct connected electric motor not shown, or by a pulley on 40 the end of the shaft turned by a belt connecting with a source of power. The shaft is mounted in bearings 15 and 16. The fan chamber 8 has a discharge opening 17 arranged tangentially with respect to the same 45 from which any suitable pipe, for instance, one made of galvanized sheet iron, not shown, will conduct the pulverized material intimately mixed with air to the place of use, deposit or separation. Mounted on the 50 shaft 14 within the pulverizing chambers are the disks 18, 19, 20 and 21 carrying the paddles 22. The disks are preferably but not necessarily carried on cast iron hubs 23, and are held to the hub by shearing bolts 24. 55 Retaining rings 25 held in place by tap screws 26, serve to hold the disk on the hub after the bolts 24 shall have sheared. The arms 27 may be either rigid or of the swing type. Angle iron palms 28 are riveted to the 60 ends of the arms of the disks, to which palms

may be bolted the paddles 22. The paddles may be secured to the disks by any other suitable means, as for instance the means shown at 22'.

Keyed to the shaft within the last chamber 70 is a fan 29 of any of the well-known designs.

The pulverizing and fan chambers are lined with plate linings 30 rolled to a circle in the pulverizing chambers and to the usual 75 spiral in the fan chamber and held in place by bolts or rivets through the lining 30 and shell 2, and held away from the shell where desired by the filler 31, or by any other suitable means.

80 One or more air inlets 32 are provided through the shell 2 into the auxiliary air chamber 7, and the inlets are provided with dampers 33 to regulate the amount of air 85 which shall be admitted. Material is fed to the pulverizer through a chute 34 by any 85 convenient form of feeding device and a slide or damper is provided in the feeding device by means of which air in regulable quantity may be admitted with the material 90 to be pulverized.

95 The foregoing construction is the best now known to me, but my invention is not limited by any specific construction, but has reference to the described adjustment of the relative diameters of disks and axial openings in diaphragms, and to the described 100 means of directing the particles toward the periphery in narrow concentrated streams.

I have found that very satisfactory results are obtained in a machine in which the pulverizing chambers are four in number, $7\frac{1}{8}$ " wide between the diaphragm in which revolve paddles 6" long axially and $3\frac{1}{2}$ " wide radially, and in which the diameters of the pulverizing chambers proceeding from the feed end to the discharge end of the pulverizer were respectively $32\frac{7}{8}$ ", $34\frac{1}{2}$ ", $36\frac{1}{2}$ " and $38\frac{1}{2}$ " and in which the radii of the disks carrying the paddles proceeding from the feed end to the discharge end of the pulverizer were $11\frac{1}{2}$ ", $12\frac{1}{2}$ ", $13\frac{1}{2}$ " and $14\frac{1}{2}$ " respectively, and in which the radii of the axial openings in the diaphragms were $13\frac{1}{2}$ ".

110 These dimensions may be varied within the aforesaid limitations keeping in mind the purpose for which the adjustment of relative diameters of disks and axial openings in the diaphragms is made.

I find also that improved results are obtained in a pulverizer in which the pulverizing chambers were four (4) in number, were of a uniform diameter of $36\frac{1}{2}$ ", $7\frac{1}{8}$ " wide between the diaphragms and in which 120 revolve paddles 6" long axially and $3\frac{1}{2}$ " wide radially and in which the radii of the disks carrying the paddles proceeding from the feed end to the discharge end of the pulverizer were $13\frac{1}{2}$ ", $13\frac{1}{4}$ ", $13\frac{1}{2}$ " and $13\frac{1}{4}$ " respectively, and in which the radii of the 125 axial openings in the diaphragms were $13\frac{1}{2}$ ".

130

axial openings in the diaphragms were 15", 14", 13" and 12 $\frac{1}{2}$ " respectively.

The class of pulverizers in which the chambers are of progressively increasing diameters is the preferable class for the application of my invention, requires less power and produces a finer powder.

The operation of my improved pulverizer is as follows, when used for pulverizing and feeding coal to a furnace to be burned in suspension in air:

Power is applied to the shaft 14 to rotate it at the proper speed, say 1400 revolutions a minute. The material to be pulverized is introduced through the chute 34, and with the material is admitted air in quantity sufficient to prevent the pulverizer from clogging,—say seven pounds of air to one of coal. The fan 29 induces a draft through the pulverizer from the feed end to the discharge end thereof. The material entering the pulverizing chamber 3 will be shattered by the rapidly revolving paddles 22, the corrugations upon the faces of which will prevent the shattered particles from being propelled by the impact axially toward the discharge end of the pulverizer and will guide them toward the periphery where they are further pulverized, by friction among the particles, and on the paddles, and by driven contact with the lining 30. As the particles of material are reduced in size the fine particles are carried by the axial air current through the opening in the diaphragm 9 into the pulverizing chamber 4, the coarser particles being again thrown by centrifugal force toward the periphery are held in the pulverizing chamber 4 for such further reduction in size as will permit the axial current to overcome centrifugal force and carry the particles through the axial opening in the diaphragm. Nearly all of the material as it leaves the chamber 3, although much reduced, is still too coarse to meet commercial requirements. At the periphery of this as of all chambers the coarser particles predominate and away from the periphery the finer particles predominate, but as the axial opening in the diaphragm 9 is larger than the disk 18 the axial air current while on its way from chamber 3 to chamber 4 is comparatively thick measured on a radial line and is not much deflected by the diaphragm 9 toward the axis of rotation, and the particles of coal or other material, while in chamber 3 and relatively large, are subjected to less centrifugal force than in the succeeding chambers all of which combines to make the carrying power of the axial air current greater between the chambers 3 and 4 than between any other pair of chambers, preventing over-load and clogging in chamber 3 where the particles are the least susceptible to flotation in air.

When the solid particles enter chamber 4

their course is moderately deflected toward the periphery by the disk 19 whose diameter preferably more nearly approaches the diameter of the opening in the diaphragm 9, the axial air current measured on a radial line becomes thinner and as it passes the disk 19 the radius of the curve of rotation is longer, centrifugal force is higher and the axial current laden with solid particles is deflected toward the axis of rotation by the diaphragm 10 by a larger angle than that of the corresponding deflection occasioned by diaphragm 9. The average size of the particles in chamber 4 is smaller than in chamber 3, they are more readily borne on with an axial air current and are less easily thrown out by centrifugal motion, but the described adjustment of parts compensates the changed condition of the material.

The solid particles and the air move through the succeeding chambers 5 and 6 in the same way, the tubular axial air current growing thinner, the waves and deflections thereof more pronounced and the radius of rotation increasing until in chamber 6 the radius of the disk 21 is longer than the radius of the axial opening in either of the diaphragms 11 or 12.

The corrugations on the paddles 22 revolving in the chambers 3, 4, 5 and 6 serve to line up in concentrated streams the solid particles of material and thus lined up the solid particles more readily overcome atmospheric resistance, escape the axial current and reach the periphery.

From the chamber 6 the axial current of air and material is drawn through the auxiliary air chamber 7, where is drawn in and added to the current such additional air as is needed for combustion, say seven pounds more of air to one of coal. The auxiliary air meets the axial current at right angles or nearly so and the two intermix to some extent in the chamber 7, and the mixture is completed in passing through the fan.

The whole mixture is then expelled through the discharge opening 17 and is conducted by the discharge pipe to the place of use, deposit or separation.

Thus, my adjustment goes to the treatment of the larger particles of coal, although some portion of the particles, already sufficient fine, go along with them.

The described adjustment of relative diameters positively directs the solid particles toward the periphery, successively lengthens the radii of the curves of rotation with no reduction in the number of revolutions, increases the centrifugal force to which the solid particles are subjected in each successive chamber, thins the tubular axial current of air on which the solid particles are borne from any chamber to the next succeeding one, and impresses upon that current, however tumultuous it may be,

waves toward and from the axis each succeeding wave being more pronounced than its predecessor, each of which elements is related to the diminishing size of the solid particles as they pass from one chamber to the next and to the increasing difficulty of separation, and with all of them the concentrated streams of particles produced by the grooved faces of the paddles coöperate. In 10 the use of the word diaphragm or diaphragms, it is not intended to include the heads at either end of the cylindrical shell in which the pulverizing is done and by the term first diaphragm I means that diaphragm through which the contents of the first chamber are discharged.

What I claim is:

1. A pulverizer comprising a chamber, adapted to permit the passage of air and 20 solids longitudinally therethrough, and rotary pulverizers mounted to operate transversely to the passage of said substances, said pulverizers provided with impact means shaped to guide material radially 25 outwardly against the inner wall of said chamber and between the outer edges of said chamber and between the outer edges of said impact means and said wall.

2. A pulverizer comprising a chamber adapted to permit the passage of air and 30 solids longitudinally therethrough, and rotary pulverizing members therein formed with radial ribs and grooves to form impact members and guides to direct solids outwardly against the inner wall of said chamber and between the outer edges of said 35 pulverizers and said wall.

3. A pulverizer comprising a chamber provided with annular pockets extending from its inner wall, and pulverizers mounted 40 to rotate in said chamber and projecting into said pockets, said pulverizers provided with radial ribs and grooves adapted to form impact members and operating to guide material within said pockets outwardly against said inner wall.

4. The apparatus substantially as defined in claim 3, together with suction means to draw material longitudinally through said chamber.

5. A pulverizer comprising a chamber through which air and solids may be longitudinally drawn, a set of annular diaphragms arranged in spaced relation and projecting from the inner wall of said 55 chamber to form annular pockets therebetween, disks mounted to rotate in said chamber, pulverizers mounted upon said disks and projecting into said pockets, the adjacent disks and diaphragms at the inlet 60 of said chamber providing a comparatively wide and tubular space for air and solid material moved therethrough, the adjacent disks and diaphragms toward the exit of said chamber providing a thin and radially

undulating tubular space for the passage of air and pulverized solids.

6. A pulverizer comprising a chamber having inlet and outlet openings, diaphragms projecting inwardly therein to form annular pockets, disks mounted to rotate in said 70 chamber and provided with pulverizers projecting into said pockets, the adjacent disks and diaphragms toward the inlet opening being widely spaced radially to form a comparatively large tubular space for the passage of air and solids and the disks and adjacent diaphragms toward the exit opening being closely related radially to form a radially undulating thinner tubular space for the passage of air and pulverized solids. 80

7. A pulverizing mill comprising a chamber, through which air and solids are adapted to be drawn, annular diaphragms projecting inwardly therein, disks provided with pulverizers, rotative in said chamber in coöperative relation to said diaphragms, the axial opening in the diaphragm toward the inlet to said chamber being larger than the adjacent disks and the axial opening of the diaphragm toward the exit of said chamber 90 being substantially the same size as the adjacent disk.

8. A mill of the class described, comprising a pulverizing chamber through which air and solids may be longitudinally drawn, 95 spaced annular diaphragms forming baffles and pulverizing chambers projecting inwardly from the wall of said chamber, disks carrying pulverizers mounted to rotate in said chamber in coöperative relation with 100 said diaphragms, the diameter of the disk at the inlet end of the chamber being less than the diameter of the opening of the next succeeding diaphragm and the diameter of the disk at the discharge end of the pulverizing 105 chamber being approximately the length of the diameter of the opening in the next preceding diaphragm.

9. A pulverizing mill comprising a chamber through which air and solids are adapted to be drawn, a series of annular diaphragms therein forming baffles and annular pockets, and a series of disks carrying pulverizers rotative therein, in coöperative relation with said diaphragms, the diameter of the disk nearest the inlet of said chamber being substantially less than the diameter of the opening in the adjacent diaphragm, and the diameter of another of said disks being about the same in length as that of the opening in the next preceding diaphragm thereto. 110 115 120

10. The method of selecting and pulverizing material in a longitudinally disposed chamber, which consists in producing a flow of air and solid material longitudinally therethrough, and subjecting material to successive transverse pulverizing actions in an elongated annular space therein which is 125

relatively thick and substantially unobstructed toward the beginning of the pul-
verizing action, and which is thin and radi-
ally undulating toward the end of the pul-
verizing action.

11. A method substantially as set forth in
claim 10 in which material is also guided
radially outwardly against the inner walls
of the chamber.

In witness whereof I have hereunto set 10
my hand at the borough of Manhattan, city
and State of New York, this 4th day of
January, 1919.

FRED'K SEYMOUR.

In presence of—

C. CURTIS,
JOHN J. RANAGAN.
